UNITED STATES PATENT OFFICE.

CHARLES L. DUENKEL, OF EAST ORANGE, NEW JERSEY.

DESIGN FOR A LAMP.

No. 38,316.

Specification for Design.

Patented Nov. 20, 1906.

Application filed October 5, 1906. Serial No. 337,643. Term of patent 7 years.

To all whom it may concern:

Be it known that I, CHARLES L. DUENKEL, a citizen of the United States, residing at East Orange, in the county of Essex and State of New Jersey, have invented a new, original, and ornamental Design for Lamps, of which the following is a specification, reference being had to the accompanying drawing, forming part thereof.

The figure is an elevation of a lamp, showing my new design.

I claim—

The ornamental design for a lamp, as shown.

CHARLES L. DUENKEL.
